DEBARKING MACHINE HAVING STAGGERED
FLAIL-CARRYING DRUMS FOR BROAD-
SIDE ATTACK ON ROTATING LOGS

James K. Williford, Hickory, Miss.

Application September 22, 1950, Serial No. 186,246

9 Claims. (Cl. 144—208)

1

This invention relates to log debarking machines, and more particularly to machines of this character which are fully automatic in their operation.

The object of the present invention is to provide a log debarking machine in which all parts of the log will be reached by the bark-removing means, and the log will be held against movement away from the bark-removing means while being worked upon. This is accomplished by working upon spaced lengths of the log sequentially, and permitting engagement of the un-worked upon sections by transporting and hold-down mechanisms.

Another object of the invention is to provide means for rotating the log while in transit through the machine and being subjected to the action of the bark-removing mechanism.

A further and important object of the invention is to provide such a machine in which the logs are loaded and carried through the machine automatically and in continuous procession, the logs having their bark removed while in forward motion, regardless of the respective diameters of adjacent logs.

A still further object is to provide means for rotating the log during debarking, which means does not interfere with the continuous forward movement of the log through the machine.

Other objects of the invention will become apparent from the following description when taken in conjunction with the drawings which accompany and form a part of this specification.

In the drawings:

Figure 1 is a side elevation of a truck with log-debarking mechanism constructed in accordance with the present invention positioned thereon;

Figure 2 is a vertical, longitudinal section taken centrally through the machine;

Figure 3 is a horizontal section taken on the line 3—3 of Figure 2;

Figure 4 is a vertical, transverse section taken on the line 4—4 of Figure 1;

Figure 5 is an enlarged vertical section taken on the line 5—5 of Figure 4; and,

Figure 6 is a vertical transverse section taken on the line 6—6 of Figure 1.

Referring to the drawings in detail, the machine of the present invention is illustrated as being portable so that it may be taken readily from one spot to another, but it will be understood that the machine may be positioned upon a permanently fixed base.

As illustrated, the debarking mechanism is mounted upon a truck chassis 1. Bolsters 2 are

2

fixed transversely of the chassis frame, and the bed rails 3 of the machine are suitably secured to them. Vertical supports 4 are connected to the bed rails, and stringers 5 connect the supports

5. The various operating parts of the machine are supported by the supports 4 and stringers 5.

The operating parts of the machine consist essentially of a loading device 6, log feeding means 7, two stages of debarking means 8 and 9, hold-down mechanism 10, and unloading skids 11. All parts of the machine are driven from a motor 12 which may be conveniently mounted on the bed rails 3 at the rear of the truck.

The loading device comprises a pair of endless chains 13, passing around sprockets 14 which are secured to a shaft 15 journaled upon forward ends of the central stringers 5. The chains are positioned on an incline, and may have their forward ends (not shown) supported from the front end of the truck frame. The chains are provided with dogs 16 to engage the logs and hold them in position as the chains travel upward.

Also mounted upon the shaft 15 is a second pair of sprockets 17. These carry the forward feed chains 18 which receive the logs from the loading chains 13 and transport them through the first stage of debarking. Chains 18 have dogs 19 for holding the logs in position. As the

20 chains 18 must support the logs over an appreciable distance, they are provided with rollers 20 which ride in channel tracks 21 which extend along the major portion of the upper flights of the chains. Channels 21 are supported at their front ends upon angle irons 22 which extend transversely across the frame and are connected to the forward vertical frame supports 4. At their rear, the channels are supported by brackets 21 secured to the stringer 5. At the rear, chains 18 pass around sprockets 23 mounted upon shaft 24 which is journaled in bearings carried by the central stringer 5.

Immediately to the rear of chains 18 there is a second pair of feed chains 25. These pass around sprockets 26 upon shaft 24, and sprockets 27 upon a shaft 28 also mounted in journals supported by stringer 5. Chains 25 have rollers 29 which travel in guide tracks 30 which are supported upon brackets 95 which are connected to the stringer 5. They also carry dogs 31.

45 It will be noted that the forward chains 18 are positioned about one-third of the distance between the side frames from each side frame, while chains 25 are located closely adjacent the frame members. The two sets of chains, in ef-

50 55

fect, form a single, continuous transporting means, as the chains overlap at the center of the machine and when chains 18 pass around sprockets 23, the logs are already supported by chains 25. The different spacing of the chain sets is to provide space for the operation of the debarking means and to permit debarking of the log from end to end, as will be described.

Operating in conjunction with the feed chain sets are the sets of log-rotating chains 32 and 33. Chains 32 are positioned parallel to, and closely adjacent to, chains 18, while chains 33 are similarly positioned with respect to chains 25. Chains 32 pass around sprockets 34 and 35 on shafts 36 and 37, and chains 33 around sprockets 38 and 39 on shafts 40 and 41. It will be noted that chains 32 and 33 are shorter than the feed chains with which they cooperate, and are positioned intermediate the lengths of the respective feed chains and substantially centered with respect to the stages of debarking (see Fig. 2). In each instance, the top flight of the log-rotating chains is positioned slightly higher than the companion flight of the feed chain. This will cause the log to be lifted from the feed chain upon the rotating chain to rest thereon, but the log will still be under the influence of the dogs on the feed chain. The log-rotating chains are moved in a direction opposite to that of the feed chains. By reason of this, the dogs upon the feed chains will keep pressing against the logs to keep them in continuous forward movement, but the log, resting upon the oppositely rotating chains, will be caused to rotate. The top flights of the chains 32 and 33 slide over supporting flanges 21' and 30' which extend from the tracks 20 and 30, respectively, so as to prevent sagging under the weight of the logs.

During the period that the logs are on the log-rotating chains 32, they pass through the first state of debarking. The debarking means 8 comprises three drums 42, spaced apart upon a shaft 43 which is journaled in bearings mounted on the bottom stringers 5. The drums are positioned on the shaft with the outside drums close to the side frames of the machine, and the third drum centrally positioned between the other two. It will be noted from Figures 3 and 4 that the feed chains 18 and the log-rotating chains 32 are positioned to pass on either side of the central drum in the spaces between that drum and the outside drums. Each of the drums has a plurality of flails 44 attached to its outer surface. The flails are arranged in banks positioned longitudinally of the drums, the banks being spaced apart circumferentially of the drums. Each bank consists of a plurality of chains, flexible in the direction of drum rotation, with each chain carrying an angular bark-removing member 45 at its outer end. It will be seen in Figures 3 and 4 that alternate banks have four chains and the intermediate banks have five. By staggering the positions of the banks, the flails present a continuous beating surface to the logs which extends substantially the width of the drums. The chains are of such length that an appreciable length of chain, as well as the angular member 45 will contact the log when the log is directly over the center of the drum. Therefore, the flails will contact the log, and remove bark, before the log reaches this central position and also while it is moving beyond it. This will insure the log making at least one complete revolution while in the area reached by the flails.

The second stage of debarking contains mechanism similar to the first, except that only two drums 46 are mounted upon the shaft 47. The drums 46 are staggered with respect to the positions of drums 42, so that the drums will overlap in their operation, and the entire length of the log will be subjected to the action of the debarking flails. In other words, the drums 46 occupy the same longitudinal positions with respect to the logs as do the feed chains 18 of the first debarking stage so that the drums may remove the bark from those portions of the log which were supported upon the feed chains during the first debarking action. Drums 46 are equipped with flails 48 similar to flails 44 of drum 42.

To insure the logs maintaining firm contact with the log rotating chains, and to prevent them from being lifted from them under the impact of the flails, mechanism is provided to press upon the tops of the logs while they are in the sphere of operation of the drums. This is the hold down mechanism 10 previously referred to.

There are two of these mechanisms, one for each stage of debarking. As the only difference between the two is that the forward one 49 is narrower than the rear one 50, for a reason which will appear later, only one will be described in detail.

30 The hold down devices consist of two truss frames 51 which are held in spaced relation by cross members 52. Each of the side frames 51 is composed of an elongated top rail 53, a short bottom rail 54 held in parallel spaced relation to the top rail by vertical struts 55, and the end members 56 which incline upwardly from the ends of the bottom rail to the ends of the top rail. The entire device is suspended from chains 57, which are connected to rods 58, which 40 bridge the upper horizontal stringers 5 of the main frame. The devices are further supported by arms 59 which are swivelly connected to shafts 60 journaled to the bottom rails of the side trusses. The upper ends of the arms are pivotally connected to shafts 61 which are journaled upon the upper stringers 5. By this arrangement, the hold down devices are freely floating and may rise and fall or tilt in a vertical plane in accordance with the size of the logs which are 50 in the machine. To enable the logs to move freely under the hold down devices, and also to assist in rotating the logs, chains 62 are provided to form the log contacting surfaces of these devices. These chains pass around sprockets 63 on shafts 55 60 and sprockets 64 on shafts 65 mounted on the bottom rails 54. Chains 62 have their bottom flights moving in a direction opposite to that of the top flights of the log rotating chains 32 and 33 so as to aid the rotating of the log.

60 As previously mentioned, all of the moving parts of the machine are driven from the motor 12. A belt 66 runs from the motor shaft around a pulley 67 mounted on the shaft 47 of the rear debarking drums. Shaft 47 also carries a sprocket 68 around which a chain 69 passes to a sprocket 70 on shaft 43 which supports the forward debarking drums. Thus, both sets of drums are driven in the same direction, and at the same speed. As indicated in Figures 1 and 2, the drums 70 rotate in an opposite direction to the travel of the logs.

Shaft 47 carries a second sprocket 71 for a belt 72 which passes around sprocket 73 on a short shaft 74 journaled upon one side of the main frame. Shaft 74 carries a sprocket 75 and chain

16 is driven by this sprocket and, in turn, drives sprocket 11 on shaft 18. Shaft 18, through sprocket 19 and chain 80, drives shaft 81 which carries spur gear 82 which meshes with gear 83 on the rear feed-chain rear sprocket shaft 28. This will drive the rear feed chains, and, as the rear feed chains and forward feed chains have sprockets on the common shaft 24, the forward chains will be driven also. This same drive will operate the loading chains, for the loading device and forward feed chains use the common shaft 15. Due to the use of the gears 82 and 83, the direction of rotation of the loading and feed-chains will be reversed to that of the debarking drums.

It is desirable that the logs be rotated in a direction opposite to that of the debarking drums, so it is necessary to drive both the log-rotating drums and the chains of the hold down devices in the same direction as the drums. To do this, power is taken from the shafts 18 and 81 which are driven from the drums. From shaft 18 a chain 84 drives shaft 85, and from shaft 85 chain 86 drives the rear log rotating chain shaft 40. Also from shaft 85 chain 87 drives the forward shaft 61 which pivotally supports the front hold down device arms 59. A chain 88, passing around sprockets on shafts 61 and 60, drives the hold down device chains 62. Another chain 89 from shaft 61 drives the forward log rotating chain shaft 36. From shaft 81, chain 90 drives shaft 61 of the rear hold down device, and from this shaft chain 91 drives the shaft 60. This completes the drive.

In operation, the motor 12 will be started which will set all of the operating parts in motion. Logs will then be loaded upon the chain 13, and the logs resting against the dogs 16 will be carried up to the feed chains 18. The logs will be pushed onto the feed chains 18 by the dogs 16 of the loader chains, and the dogs 19 of feed chains 18 will contact the rear of the logs to push them through the machine. When the log-rotating chains 32 are reached, the logs, being pushed forward by the feed chain dogs 19, will ride up on the elevated top flights of the log-rotating chains, remaining, however, in contact with the feed chain dogs so that they will be moved continuously forward. While the logs are on the log-rotating chains, they pass under the hold down device 49. Due to the floating mount for the hold down device, this mechanism may tilt or rise or fall freely in a vertical plane. The inclined end members 56 of the bottom rail will provide camming surfaces, so that if the forward end of the device is in a low position an approaching log will strike the incline and cause the device to ride up over the log. The floating mount will permit the device to contact two logs of different diameters simultaneously, and shift its position as the logs move through the machine to retain its contact. As previously described, the log-rotating chains are moving reversely to the feed chains, and the hold down chains are moving in a direction to assist in the rotative movement of the logs which is initiated by the log rotating chains.

During the time that the logs are under the influence of the rotating chains, they pass over the first debarking drum 42. These drums are so positioned that their flails 44 will strike the logs during an appreciable distance of log travel. As the logs are being rotated, the flails will have an opportunity to strip the bark from the entire perimeter of the log in the areas in which

they operate. Each drum 42 is sufficiently wide to carry flails which will contact slightly more than one-fifth of the log length. The feed and rotating chains occupy positions between the drums so that they do not interfere with the action of the flails.

After the logs pass through the first stage of debarking, they have had their bark removed from their end and center sections, the bark 10 remaining on short sections intermediate the ends and center. The second sets of feed and rotating chains are more widely spaced apart than the first, so that they may contact the logs on their already peeled end sections. This permits 15 uninterrupted operation of the second stage drums on those sections of the logs upon which the bark remains. These drums 46 are transversely spaced to occupy positions intermediate the drums of the first stage, so that all of the 20 remaining bark may be removed.

After the log is completely debarked it is pushed from the feed chains 25 by the dogs 31 onto the skids 11. The logs will roll down the skids to be stacked in any convenient place.

The debarking machine here disclosed, being mounted upon a truck chassis, is freely moveable from place to place, thus eliminating the necessity for transporting the logs to debarking apparatus. The device is fully automatic, and 30 logs as they are cut may be placed upon the loading chains and will emerge from the machine fully stripped of their bark ready for transportation to a place of storage or to a pulp mill.

While one practical embodiment of the invention 35 has been disclosed herein, it will be understood that this is merely by way of example, and various changes may be made from this precise showing within the scope of the appended claims.

What is claimed is:

1. In log debarking apparatus, feed means to transport logs through the apparatus along a predetermined path with the longitudinal axes of the logs transverse to said path, at least two 45 rotatable drums carrying flails and being positioned so that said flails strike logs being carried on said feed means, said drums having their axes of rotation perpendicular to the path of the feed means, said drums being spaced apart in the direction of said path and staggered transversely to said path, means to rotate said logs while in the zones of said flail-carrying drums, said feed means being in at least two sections with the respective sections staggered in accordance with the staggered positions of the flail-carrying drums with which they cooperate.

2. In log debarking apparatus, feed means comprising a pair of spaced chains to support logs positioned transversely thereof and having 60 upstanding dogs to engage the rear surfaces of said logs as the chains move forward, log-rotating chains having their upper flights elevated above said feed chains to lift the logs from said feed chains while the logs remain in contact 65 with said dogs on said feed chains, said log-rotating chains moving in a direction opposite to that of said feed-chains, and a rotatable drum carrying flails and having its axis of rotation transverse to the direction of travel of said 70 chains, said drums being positioned so that said flails strike logs supported on said log-rotating chains.

3. In a log debarking apparatus as claimed in claim 2, a floating hold down device positioned above said log-rotating chains and having

chains to engage the upper surfaces of logs supported on said log-rotating chains, the log-contacting surfaces of the log-rotating and hold down chains moving in opposite directions.

4. In log-debarking apparatus as claimed in claim 2, a floating hold down device positioned above said log-rotating chains and having chains to engage the upper surfaces of logs supported on said log-rotating chains, the log-contacting surfaces of the log-rotating and hold down chains moving in opposite directions, said hold down device having cam leading and trailing surfaces to raise the device to rest upon a log and to lower the device when the log has passed.

5. In log-debarking apparatus, feed means comprising a pair of spaced chains to support logs positioned transversely thereof and having upstanding dogs to engage the rear surfaces of said logs as the chains move forward, log-rotating chains having their upper flights elevated above said feed chains to lift the logs from said feed chains while the logs remain in contact with said dogs on said feed chains, said log-rotating chains moving in a direction opposite to that of said feed chains, rotatable drums carrying flails and having their axes of rotation transverse to the direction of travel of said chains, said drums being positioned so that said flails strike logs supported on said log-rotating chains, said drums being spaced apart in an axial direction and said feed chains and log-rotating chains occupying vertical planes intermediate said drums, a second set of feed chains in longitudinal continuation of the first and transversely offset with respect thereto, log-rotating chains in association with said second feed chains, and flail-carrying drums positioned beneath said second log-rotating chains and in transversely staggered and overlapping relation to said first drums.

6. In log-debarking apparatus as claimed in 40

claim 5, a floating hold down device positioned above each of said sets of log-rotating chains and having chains to engage the upper surfaces of logs supported on said log-rotating chains, the log-contacting surfaces of the log-rotating and hold down chains moving in opposite directions.

7. In log-debarking apparatus as claimed in claim 5, a floating hold down device positioned above each of said sets of log-rotating chains and having chains to engage the upper surfaces of logs supported on said log-rotating chains, the log-contacting surfaces of the log-rotating and hold down chains moving in opposite directions, 15 said hold down devices having cam leading and trailing surfaces to raise the devices to rest upon a log and to lower the devices when the log has passed.

8. In log-debarking apparatus as claimed in claim 5, a loading conveyor to raise logs to said feed chains, and unloading skids to discharge logs therefrom.

9. In log-debarking apparatus as claimed in claim 5, said apparatus being mounted upon a wheeled chassis, a loading conveyor supported at the front of said chassis to raise logs to said first set of feed chains, and unloading skids supported at the rear of said chassis to receive logs from said second set of feed chains.
